[57] ABSTRACT

A mechanism for bodily transporting a transducer over a closed, elongated path in which one portion of an arm is slidably coupled to a rotatable member. A transducer carrier attached to the arm is transported over a path defined by the composite motions of the two portions of the arm, thus carrying the transducer in a closed elongated loop.

MECHANISM FOR CARRYING A TRANSDUCER OVER AN ELONGATED PATH

BACKGROUND OF THE INVENTION

The invention is related broadly to machine elements and mechanisms and more specifically to mechanisms for transporting transducers or the like over predetermined closed pathways.

In adapting banking and accounting procedures to electronic automation, an attempt is made to use as many forms and books of the old procedures as possible in order to reduce the expense and time involved with creating new ones. Such a situation arises in banking when it is desired to electronically automate the credit and debit procedures of various accounts. In order to use the old bank books for the new automated procedures a portion of the books must be provided on which information can be electronically written and from which information can be read. One solution is to attach a magnetic strip to the cover of the old bank books for accommodating apparatus that aligns a read-write transducer with the strip and moves one with respect to the other over the length of the strip.

The shape in which the magnetic strip is placed on the book is important, for if the strip were disposed in a straight line, the length of the strip and consequently the amount of information the strip could contain would be relatively small. If, instead, the strip were formed of a circle and the transducer rotated from the center thereof, a provision would have to be made for costly lead connections to the rotating transducer.

To avoid having to rotate the transducer over a circular path it could rather be fixed to apparatus that would move it bodily about a circle from outside the interior thereof. Then, however, another problem can be recognized. Most magnetic transducers are designed to operate only in certain ranges of positions relative to their motion over a magnetic medium or strip. When a transducer is effectively fixed in position relative to a circular strip, then bodily rotated about the circle, the transducer equally takes up all positions relative to its motion and consequently spends a significant amount of travel time outside its operative position range.

SUMMARY OF THE INVENTION

In view of the problems described above, it is an object of the present invention to trace a closed path over which a non-rotatable magnetic transducer may be moved while maintaining the transducer within its operative position range for a maximum period of travel time.

It is another object of the invention to securely carry a transducer over said path.

It is still another object of the invention to transport a transducer through its operative position range at a nearly constant velocity.

The invention accomplishes these and other objects by combining a member that is rotatable about a stationary axis with an arm that has a rotated portion pivotally coupled with the rotatable member. Another or guided portion of the arm is engaged with a guide means that guides the arm along a predetermined path. The rotation of the rotatable member transports a transducer carrier attached to the arm about a closed, elongated loop. The relationships between the length of the arm, the position, height and angle of the trans-

ducer carrier with respect to the arm may be adjusted so that a path is traced having only a small section in which the transducer is positioned outside its operative position range and in which the velocity of the carrier over the operative section of the path has a minimum variance.

BRIEF DESCRIPTION OF THE DRAWINGS

To facilitate a more complete understanding of the invention a preferred embodiment will hereinafter be described in connection with the drawings in which:

FIG. 1 is a front elevation of a preferred mechanism;

FIG. 2 is a front diagrammatical view of the mechanism showing two traces each resulting from a carrier of different length;

FIG. 3 is a diagrammatical view of the mechanism showing two traces each resulting from a guide in a different position;

FIG. 4 is a diagrammatical view of the mechanism showing two traces each resulting from an arm of different length;

FIG. 5 is a diagrammatical view of the mechanism showing a trace resulting from a curved guide; and

FIG. 6 is a diagrammatical view of the mechanism showing twelve traces each from a different carrier positioned at equally spaced angles with respect to the arm.

DESCRIPTION OF THE PREFERRED EMBODIMENT

Referring to the drawings wherein like reference characters designate identical elements in the various figures, and particularly to FIG. 1, an arm 10 has a camming projection or shaft 12 extending transversely from one end or guided portion 14 thereof. The camming shaft 12 engages a guide or slot 16 in a supporting plate 18, the slot having a width slightly greater than the diameter of the shaft so that it may slide freely therein. The slot 16 is disposed on a guide line 20 and spaced apart from a rotatable member or crank 22. A rotated portion 24 of the arm is pivotally connected at a pivot point 25 by means of a pivot shaft 26 to the rotatable crank 22, the crank being rigidly mounted to a crank shaft 28 projecting through a bearing in the supporting plate 18. The crank shaft 28 is rotatable about a stationary axis 30 and upon such rotation carries the crank with it in clockwise rotation.

A transducer carrier 32 is fixedly connected with the rotated portion 24 of the arm 10 and extends normally therefrom. A free end 34 of the carrier 32 is configured in an appropriate shape for supporting a transducer 36.

With the transducer 36 mounted on the free end 34 of the carrier 32, a rotation of the crank 22 causes the guided portion 14 of the arm 10 to reciprocally slide within the slot 16 and the rotated portion 24 of the arm to rotate with the crank. The transducer 36 is consequently carried in a path 38 that is characterized by the composite of these two motions as altered by the geometry of the carrier 32.

OPERATION

Assuming the geometric relationships to be as shown in FIG. 1, the mounted transducer is transported in a closed, elongated loop on which path 38 could ad-

vantageously be disposed a magnetic information-bearing strip. As can be observed in FIG. 1, the path 38 or trace of the free end 34 of the carrier 32 has very short end portions 39 over which a mounted transducer 36 would be outside its operative range of positions relative to its motion over the magnetic strip.

In addition the speed of the carrier 32 over the long portions of the trace 38 has only a small variation, assuming a constant speed crank 22. This permits close to optimum information recording density on the magnetic strip.

There are many variations that can be made to the geometric relationship of the mechanism. Some combinations of the relationships provide better traces for the purpose of the present invention while other relationships result in traces with undesirable characteristics. Some of these various relationships will hereinafter be described and their advantageous aspects as well as their undesirable ones will be pointed out. The description will refer to ones of FIGS. 2-6 each of which are simplified diagrams similar to FIG. 1 in which the carrier 32, arm 10 and guide 16 are shown as dark lines and the circular path of the crank 22 is illustrated by a dotted line.

Assuming that all other relationships remain constant, if the length of the transducer carrier 32 relative to the length of the arm 10 is increased, the trace elongates, as shown in FIG. 2. As heretofore described the elongated trace is preferable in that the end portions thereof are very short in relation to the elongated portions where the transducer 36 is transported in a position within its operative range. It has been found that when the carrier 32 and the arm 10 are disposed at right angles, as shown, the carrier should be at least as long as the arm to provide a trace of sufficient elongation. As an example, FIG. 2 shows the resulting traces 40, 42 of a short and a long carrier 32, respectively.

Another characteristic that can be altered in the mechanism is the distance of the guide or slot 16 from the center of rotation of the rotatable member or crank 22. As illustrated in FIG. 3, when all else remains constant and the slot 16 is moved from a position intersecting the center of rotation outwardly, the volume enclosed by the traces 44 and 46 increases as the distance of the slot from the center of rotation increases. In addition there is a slight clockwise change of position of the trace with respect to the center of rotation as the slot distance is increased.

The relationship between the length of the arm 10 and the diameter of the circle of rotation of the rotatable member or crank 22 is shown in FIG. 4. As can be seen, when the arm 10 is long relative to the diameter of the circle or conversely, the circle is small relative to the length of the arm the volume enclosed by the trace 48 of the mechanism is small. When the arm is shortened the volume enclosed by the trace, as at 50, increases while the shape of the trace remains nearly constant. As it is the shape of the trace rather than the volume enclosed by it that achieves the desirable reading and writing characteristics, this is the most important consideration in the design of the mechanism. Although the latter two variables (slot position and length of arm) only affect the size of the trace, they are important in conforming the trace to the size of the 65

medium and the quantity of recorded information required by the user.

In the examples described so far the guide or slot 16 has been disposed in a straight line, although there are a multitude of shapes the slot 16 may assume and have acceptable results. A slot disposed in a curved guide line 20, as illustrated in FIG. 5, achieves a trace 52 having the desirable characteristics heretofore described.

Perhaps the most crucial of the relationships in determining the shape of the resulting trace is the angle of the transducer carrier 32 with the arm 10. As can be noted in FIG. 6, when all other components of the mechanism are held constant and the carrier 32 rotated about its junction with the arm 10 there is a certain range of carrier angles which result in markedly unsymmetrical traces as at 54-60, while in another range of carrier angles the resulting traces 62-67 have more desirable elongated, symmetrical shapes. A relationship has been found that approximates the range of angles at which the carrier 32 may extend from the arm 10 and produce traces with desirable characteristics. When the pivot point 25 of the arm 10 with the crank 22 is positioned on a center line 72 that perpendicularly intersects the guide line 20 through the center of rotation of the crank 22, the desirable range of angles is that 180° sector on the opposite side of the center line from the junction of the arm with the slot 16.

The foregoing examples illustrate some of the many variations in which the present invention may be embodied. The length of the carrier 32, the shape of the slot 16 and the distance thereof from the center of rotation of the crank 22, the length of the arm 10 and the angle of the carrier with the arm may all be modified in accordance with the teaching of the foregoing description in order to obtain a particular shape of trace to suit a user's need.

What is claimed is:

1. In apparatus for writing and reading data on and from a magnetic strip, a mechanism for bodily transporting a transducer over a closed, elongated loop during the process of reading or writing, said mechanism comprising:

a member rotatable about a stationary axis, guide means disposed on a guide line, said means being spaced apart from said rotatable member, an arm having a guided portion pivotally and slidably engaged with said guide means for displacement along said guide line and a rotated portion pivotally coupled at a pivot point to said rotatable member, the rotation of said member being operative in imparting a reciprocal motion to said arm, said motion being characterized by the composite of the motions imparted to said rotated and said guided portions of said arm, and

a transducer carrier joined to said arm at the rotated portion thereof for displacement therewith, said carrier having a mounting for supporting the transducer, whereby the reciprocation of said arm conveys the transducer mounted on said carrier in a closed, elongated loop.

2. A mechanism as defined in claim 1 wherein said carrier extends normally from said arm.

3. A mechanism as defined in claim 2 wherein said carrier is at least as long as said arm.
